(57) **CLAIM**

We claim the ornamental design for a switch guard, as shown and described.

DESCRIPTION

FIG. 1 is a front, perspective view of a transparent switch guard according to the present invention;
FIG. 2 is a front elevational view thereof;
FIG. 3 is a rear elevational view thereof;
FIG. 4 is a left side elevational view thereof;
FIG. 5 is a right side elevational view thereof;
FIG. 6 is top plan view thereof;
FIG. 7 is a bottom plan view thereof;
FIG. 8 is a front, perspective view of another embodiment, a non-transparent switch guard, according to the present invention;
FIG. 9 is a front elevational view thereof;
FIG. 10 is a rear elevational view thereof;
FIG. 11 is a left side elevational view thereof;
FIG. 12 is a right side elevational view thereof;
FIG. 13 is top plan view thereof; and,
FIG. 14 is a bottom plan view thereof.
